UNITED STATES PATENT OFFICE.

MARGARET C. MONTVILLE, OF KANSAS CITY, MISSOURI.

FOOT REST.

Application filed September 28, 1921. Serial No. 503,837.

To all whom it may concern:

Be it known that I, MARGARET C. MONTVILLE, a citizen of the United States, residing at Kansas City, in the county of Jackson and State of Missouri, have invented certain new and useful Improvements in Foot Rests, of which the following is a specification.

My invention relates to foot-rests or supports for use in shoe-polishing establishments, adapted to afford a support for the foot of a person while a shoe is being polished.

The primary object of my invention is to provide a foot rest or support which is adapted to be swung out of the way of the patron when the polishing of the shoes of the latter has been completed to permit the person to conveniently and safely move out of the way of such rest or support and thus prevent accidental tearing of the clothing and also prevent bodily injury.

A further object of the invention is to provide a foot rest or support of the character described which shall be of extremely simple and inexpensive construction and which can be easily and quickly operated when it is desired to swing the rest out of the way of a person when in the act of leaving the stand or obtaining access thereto.

The invention consists in the novel construction, arrangement and combination of parts substantially as hereinafter fully described, illustrated in the accompanying drawings and pointed out in the appended claims.

In the drawings—

Fig. 1 is a side elevation of my foot-rest or support in raised position.

Fig. 2 is a view, partly in elevation and partly in section, of the device as seen in Fig. 1.

Fig. 3 is a top plan view of the device as seen in Fig. 1.

Fig. 4 is a top plan view showing the device swung down out of the way.

I will now describe my device in detail.

1 indicates a portion of an elevated stand or platform upon which my device is adapted to be mounted. Said device comprises a base 2 adapted to be rigidly secured in any suitable manner to the stand, as by means of a bolt 3 projecting through an aperture 4 in the base and threaded to receive a nut 5. The base is provided with cheeks or abutments 6 and 7, each of which

is provided with a squared recess 8, the recess in abutment 6 being upon the inner face of the latter and the recess in abutment 7 being upon the outer face thereof.

9 indicates a foot-supporting member, the portion 10 whereof is adapted to directly receive and support the shoe while the same is being polished. The member 9 also comprises a depending portion 11 carrying the portion 10, said portion 11 being of any suitable construction or configuration but embodying essentially two legs 12, 13, the lower ends of which are shaped to snugly yet removably fit within the recesses, said lower ends of the legs being adapted to be moved laterally out of the recesses, in the manner and for the purpose hereinafter set forth.

The height of the portion 11 may be varied but it should be of such height that when in a vertical position the foot-receiving portion 10 will be at such a height above the stand as to make it convenient for the person to rest his foot upon said portion 10.

The member 9 is adapted to have a pivotal connection with the base 2 and this result may be obtained in any suitable manner. I have shown a means for pivotally mounting the member 9, comprising lugs 14, 15, projecting laterally from the lower ends of the legs 12, 13. The lug 14 projects loosely within an aperture 16 in the base while the lug 15 projects loosely within an aperture 17 in the base, said lug 15 being of sufficient length to project somewhat beyond the outer face of the abutment 6.

18 indicates a coiled spring, one end of which encircles a lug 19 projecting from the inner face of the abutment 7 and bearing against the latter, while the opposite end of the spring encircles a lug 20 on the inner face of leg 12 and bears against the latter.

The projecting portion of the lug 15 constitutes a means for pressing the member 9 laterally to cause the lower ends of the legs to move out of the recesses. When this has occurred the member 9 may be swung down into a horizontal position so as to be out of the way of a person stepping onto or off of the stand.

When it is desired to use the member 9 to support the foot, it may be swung upwardly until the lower ends of the legs register with the recesses 8, when the spring 18 will shift the member 9 laterally to cause the lower ends of the legs to spring into said recesses,

5 said spring serving to prevent accidental lateral movement of member 9 which might release the legs, and by reason of the squared recesses and lower ends of the legs the member 9 will be held firmly in its vertical position while in use.

10 The lugs 14 and 15 constitute pivots for the member 9 in its swinging movements, said lugs being of sufficient length to remain within the apertures of the abutments after the legs of member 9 have been moved out of engagement with the recesses.

15 What I claim and desire to secure by Letters Patent is:

15 1. In a device of the character described, the combination with a base, of a foot-supporting member having a pivotal connection with the base, means for holding said member in upright position, and means for 20 yieldingly maintaining said member in engagement with said holding means, said foot-supporting member being shiftable laterally to free it from its holding means and permit it to be swung downwardly.

25 2. In a device of the character described, the combination with a base having abutments provided each with a recess, of a foot-supporting member having legs pivotally connected with the base, the lower ends of 30 said legs being adapted to fit within the said recesses when said member is in upright position, said member being shiftable laterally to release the legs from the recesses and permit it to be swung downwardly.

35 3. In a device of the character described, the combination with a base having abutments, one of said abutments having a recess

40 in its inner face and the other abutment having a recess in its outer face, of a foot-supporting member having legs pivotally connected with the base, the lower ends of the legs being adapted to fit within the said recesses when said member is in upright position, and means for yieldingly maintaining 45 the legs of said member within said recesses.

4. In a device of the character described, the combination with a base having abutments provided each with a recess, of a foot-supporting member having legs pivotally connected with the base, the lower ends of 50 said legs being adapted to fit within the said recesses when said member is in upright position, said member being shiftable laterally to release the legs from the recesses, and a spring bearing at one end upon one of the 55 legs and at the other end upon one of the abutments and operating to yieldingly hold the lower ends of the legs within the recesses.

5. In a device of the character described, the combination with a base having abutments each provided with a recess, of a laterally-shiftable foot-supporting member having legs whose lower ends are adapted 60 to fit within the recesses when said member is in upright position, and lugs on the legs 65 extending into apertures in the abutments to provide a pivotal connection for the said member with the base, one of said lugs extending beyond its respective abutment to provide means for shifting the foot-supporting member laterally to free the legs from the said recesses.

In testimony whereof I affix my signature.
MARGARET C. MONTVILLE.
